W. E. McDONELL,
EYEGLASSES AND SPECTACLES,
APPLICATION FILED JUNE 13, 1914.

1,170,302.

Patented Feb. 1, 1916.

UNITED STATES PATENT OFFICE.

WILLIAM E. McDONELL, OF ROCHESTER, NEW YORK, ASSIGNOR TO ROCHESTER SPECTACLE CO., OF ROCHESTER, NEW YORK, A CORPORATION OF NEW YORK.

EYEGLASSES AND SPECTACLES.

1,170,302.

Specification of Letters Patent.

Patented Feb. 1, 1916.

Application filed June 13, 1914. Serial No. 844,875.

To all whom it may concern:

Be it known that I, WILLIAM E. McDONELL, of Rochester, in the county of Monroe and State of New York, have invented 5 a new and useful Improvement in Eye-glasses and Spectacles, which improvement is fully set forth in the following specification and shown in the accompanying drawings.

10 The present invention relates to eyeglasses and spectacles and more particularly to the pads and nose guards therefor, an object of the invention being to provide for mounting the pad in such a manner as to eliminate 15 the necessity of separate fastening devices for securing the pad to the mounting.

Another object of the invention is to provide an improved pad which may be made from a sheet metal blank.

20 Still another object of the invention is to provide an improved construction which may be readily adjusted to conform to the taper of the nose.

To these and other ends, the invention 25 consists in certain parts and combinations of parts all of which will be hereinafter described, the novel features being pointed out in the appended claims.

In the drawings: Figure 1 is a front 30 view of spectacles embodying the present improvements; Fig. 2 is a top view of the same spectacles with one of the pads removed; Fig. 3 is a section on the line *a—a*, Fig. 1; Fig. 4 is a section on the line *b—b*, Fig. 2 through one of the pads; Fig. 5 is a rear view of one of the pads; Fig. 6 is a plan view of a blank from which the pad shown in Fig. 5 is formed; Fig. 7 is a plan view of a blank which will form another embodiment of the present improvements; Fig. 8 is a top view of still another embodiment of the invention in which the pads are mounted upon the bridging portion of a spectacle mounting; and Fig. 9 is a view of a guard adapted to be used on spectacles and eyeglasses and having the invention embodied in the upper pad thereof.

In the embodiment of the invention illustrated in Figs. 1 to 6, A indicates the lenses, 50 B the lens clamps to which the temples C are pivoted, and D the lens clamps or lens attaching devices connected by the bridging portion E which has vertical coils F at

its ends. Connected to each of the coils F is a guard supporting arm which extends 55 downwardly at 1, thence outwardly and rearwardly at 2, thence upwardly at 3, thence inwardly at 4 and finally rearwardly at 5, the rearwardly extending portion providing a bearing portion for the guard and 60 having the portion 4 extending laterally thereto.

The guard pad is provided with a supporting portion 6 preferably in the form of a split sleeve surrounding the bearing portion 5 and having a lateral opening 7 through which the portion 4 extends to limit the movement of the guard pad on the bearing portion 5, this opening preferably being larger than the laterally-extending portion 70 in order to permit the guard pad to rock on the bearing 5. The guard pad preferably embodies two nose bearing portions 8 and 9 extending in opposite directions from the sleeve 6 and preferably connected to the 75 sleeve in opposite sides of the split by weakened portions 10, thus permitting the bearing portions 8 and 9 to be relatively adjusted. In this instance, the nose bearing portions of the pad and the supporting 80 sleeve 6 are formed from a single blank of ductile sheet metal, this blank being illustrated in Fig. 6 and being bent between the nose bearing portions 8 and 9 to provide the sleeve 6, the weakened portions being 85 formed by providing transverse slots 11 in the blank. With this arrangement, it is possible to adjust the nose bearing portions 8 and 9 without spreading the split sleeve on its bearing. This pad may also be formed 90 in the manner illustrated in Fig. 7 in which the nose bearing portions 8 and 9 are separated from the sleeve portion 6 by weakened portions 11^a formed by reducing the metal at the inner ends of the nose bearing 95 portions 8 and 9. Instead of an elongated opening as in Fig. 6, a circular opening 7^a is provided which conforms to the exterior of the laterally-extending portions and prevents the rocking of the pad. 100

In the embodiment shown in Fig. 8, the lenses A are connected by an arched or bridging portion 12 which has forwardly-extending arms 13 connected at their outer ends to the lens attaching devices B. The 105 guard pads turn directly on the arched or

bridging portion and are formed in the manner shown in Fig. 6 except that in each, the slot 7 occurs near the rear end of the sleeve 6 instead of at the forward end as shown 5 in Figs. 1 to 5. The laterally-extending portion which limits the rocking movement of the guard pad is formed by the adjacent outward bend 14 which connects the bridging portion 12 with the adjacent forwardly- 10 extending arm 13.

In the embodiment shown in Fig. 9, the invention is embodied in the upper pad of a nose guard which is also provided with a lower pad. In this embodiment, 15 indicates the supporting arm of the guard, 16 the lower pad formed in one piece with an arm 17 which extends upwardly from the supporting arm thence rearwardly and has a bearing portion 18 turning in the 20 sleeve 6, the extreme end of the bearing portion being provided with a laterally-extending portion 19 which works in the laterally-opening slot 7 of the sleeve 6. This pad is identical in construction with the pad 25 illustrated in Fig. 5 except that it is smaller in size.

In all of the illustrated embodiments of the invention, the pad has relatively adjustable nose-bearing portions extending in 30 opposite directions from the supporting portion in the form of a sleeve, the sleeve preferably being formed by bending flat stock at an intermediate point and being preferably connected to the nose-bearing portions 35 by weakened portions which permit the relative adjustment of the nose-bearing portions. The guard pad either may be stationary on the mounting, or it may rock. In both instances, it is preferred to provide 40 the supporting sleeve with the lateral opening through which the laterally-extending portion on the mounting may extend, this opening, in one instance, being larger than the laterally-extending portion to permit the 45 rocking of the pad.

The guard pad as a whole is simple and inexpensive to manufacture as it may be made from a single blank of sheet metal. The construction also permits the pad to be 50 attached to the mounting without provision of separate or extra fastening devices.

What I claim as my invention and desire to secure by Letters Patent is:—

1. In combination with a suitable bearing, a guard or pad for eyeglasses and spectacles formed from a single blank of sheet material and embodying two relatively adjustable nose bearing portions and a split supporting sleeve formed by bends in the stock between the nose bearing portions and 55 passed about the bearing.

2. A guard or pad for eyeglasses and spectacles formed from a single blank of sheet material and embodying two relatively adjustable nose bearing portions and a supporting sleeve formed by bends in the stock between the nose bearing portions, the stock 60 having weakened portions between the sleeve and the nose bearing portions.

3. In eyeglasses or spectacles, the combination with a bearing and a laterally-extending portion at one end of the bearing, of a guard pad having a sleeve fitting around the bearing, said sleeve having a lateral opening which receives the laterally-extending 75 portion at the end of the bearing.

4. In eyeglasses and spectacles, the combination with a bearing and a laterally-extending portion at one end of the bearing of a guard pad having a sleeve fitting the 80 bearing, said sleeve having a lateral opening which receives the laterally-extending portion at the end of the bearing, said opening being larger than the laterally-extending portion to permit the guard pad to rock on 85 the bearing.

5. In eyeglasses and spectacles, the combination with a bearing and a laterally-extending portion at one end of the bearing, of a guard formed from a single blank of 90 sheet material and embodying two nose bearing portions, and a supporting sleeve formed by bends in the stock between the nose bearing portions, said sleeve fitting around said bearing and having a lateral 95 opening through which the laterally-extending portion projects.

WILLIAM E. McDONELL.
